UNITED STATES PATENT OFFICE.

FRANKLIN A. LUCE, OF CHICAGO, ILLINOIS.

DESIGN FOR AN APPAREL-BELT.

SPECIFICATION forming part of Design No. 35,706, dated February 11, 1902.

Application filed January 15, 1902. Serial No. 89,926. Term of patent 3½ years.

To all whom it may concern:

Be it known that I, FRANKLIN A. LUCE, a citizen of the United States, residing at Chicago, in the county of Cook and State of Illinois, have invented and produced a new and original Design for Apparel-Belts, of which the following is a specification, reference being had to the accompanying drawings, in which—

10 Figure 1 is a perspective view showing my new design. Fig. 2 is a sectional view on line *xx* of Fig. 1, and Fig. 3 is a sectional view on line *yy* of Fig. 1.

15 My invention relates to a new and original design for apparel-belts, and the essential feature thereof resides in an apparel-belt of uniform width from end to end and having upon its outer surface a longitudinally-elongated appearance and having at the front portion and near one of the ends thereof a pocket portion on the inner face of the belt, said pocket portion extending below the lower edge of the belt and forming an ornamental and attractive feature of the belt.

20 Referring to the accompanying drawings, A indicates the belt-body, upon the material

composing the outer face of which is formed a series of tucks *a*, that extend longitudinally of the belt, such tucks standing out sufficiently to give the belt a longitudinally-corrugated appearance and being parallel with each other from end to end of the belt, the two ends of the belt being when brought together substantially parallel with each other.

25 *b* indicates a pocket portion on the inner face of the belt-body, the lower end *b'* of which extends below the lower edge of the belt at the front portion of the belt and near one of the ends thereof, said lower end having rounded corners.

30 Having described my invention, what I claim as new, and desire to secure by Letters Patent, is—

35 The design for an apparel-belt, as herein shown and described.

40 In testimony whereof I have hereunto signed my name to this specification in the presence of two subscribing witnesses.

45 FRANKLIN A. LUCE.
